UNITED STATES PATENT OFFICE.

OSWALD GUSTAV BARTUSCH, OF NEW YORK, N. Y.

NUMBERING APPARATUS.

No. 861,794.

Specification of Letters Patent.

Patented July 30, 1907.

Application filed January 25, 1906. Serial No. 297,794.

To all whom it may concern:

Be it known that I, OSWALD GUSTAV BARTUSCH, a citizen of the United States, and a resident of the city of New York, borough of Brooklyn, in the county of 5 Kings and State of New York, have invented a new and Improved Numbering Apparatus, of which the following is a full, clear, and exact description.

The object of the invention is to provide a new and improved numbering apparatus, more especially designed for use in printing presses to consecutively number the printed sheets, and arranged to permit the use 10 of a prefix forming part of the actuating mechanism for the numbering wheels and interchangeable with a non-prefix part automatically covered up during the passage 15 of the inking rollers to prevent inking of the said non-prefix part without cutting the inking rollers or requiring the use of a frisket.

The invention consists of novel features and parts and combinations of the same which will be more fully described hereinafter and then pointed out in the claims.

A practical embodiment of the invention is represented in the accompanying drawings forming a part of this specification, in which similar characters of reference indicate corresponding parts in all the views.

25 Figure 1 is a plan view of the improvement, showing the non-prefix actuating part in position; Fig. 2 is an end elevation of the same; Fig. 3 is a cross section of the same, on the line 3—3 of Fig. 1; Fig. 4 is a similar view of the same, on the line 4—4 of Fig. 1; and Fig. 5 is a 30 perspective view of the interchangeable prefix actuating part.

The numbering apparatus is mounted on a suitably constructed casing A, in which is journaled a shaft B for the numbering wheels C to turn on, the said numbers 35 bearing wheels being provided with the usual ratchet-wheels D engaged by pawls E' held on a pawl frame E mounted to swing on the shaft B as a fulcrum. The ratchet-wheels D are also engaged by the usual spring-pressed dogs F for preventing accidental return movement of the numbering wheels C.

40 The pawl frame E is preferably made U-shape, and one of its side arms is provided with a friction roller E² engaging a recess G' in a plate G mounted to slide up and down on the casing A and having an elongated slot 45 G² for the passage of the shaft B, as plainly illustrated in Fig. 3.

The upper end of the plate G is provided with an apertured offset G³, to which is adapted to be coupled, by a pin H, either of the parts I or I', of which the part I is 50 the non-prefix part, while the part I' is the prefix part having the usual type indicating "No." Each of the parts I and I' is provided with apertured offsets I², through which passes the pin H, also passing through the apertured offset G³, to securely lock the correspond-

ing part I or I' to the plate G. Each of the parts I and I' is also provided with a downwardly-extending arm I³ fitted to slide in a suitable guideway A' formed at one end of the casing A. Springs J set in the casing A press against the under side of the corresponding part I or I', so as to normally hold the part in an uppermost position, and with it the plate G; and when the part I or I' is pressed by a movable part of the printing press, then this part I or I' and the plate G coupled to the part are moved downward, to impart a swinging motion to the pawl frame E. When the printing press part has left 60 the part I or I', then the springs J return the part I or I' and the coupled plate G, so that a return swinging motion is given to the pawl frame E, which, by its pawls E', now turns the end numbering wheel C.

In order to limit the return or upward swinging motion of the plate G and its part I or I', a hook K is provided, fulcrumed on the casing A (see Fig. 3) and hooking into a pin K' projecting from the plate G.

As illustrated in Figs. 1, 2, 3 and 4, the part I has a raised blank portion I⁴ engaged by the movable 75 part of the printing press, and when in a lowermost position the upper face of this raised portion I⁴ is on a level with the numbers of the numbering wheels now on top and in printing position. In a like manner the part I' is provided with a removable prefix 80 type I⁵, adapted to be engaged by the movable part of the printing press, to actuate the numbering wheels by way of the pawl frame E, pawls E' and plate G, as previously described, the said type I⁵ being type-high when in a lowermost position; that is, in alignment with the numbers on the numbering wheels C in printing position. Now, it is evident that by the use 85 of the coupling pin H, either of the parts I or I' can be coupled to the plate G, and in case the part I is coupled to the plate G by the pin H and it is desired that the raised portion I⁴ should not be inked by the inking rollers inking the numbers of the numbering wheels C, then it is necessary to cover up the said raised portion I⁴ during the passage of the inking rollers. For this purpose the following arrangement is 90 made:

On the part I, on opposite sides of the raised portion I⁴, are arranged covering cups L and L', fulcrumed at L² and L³ to the part I and normally held in an open position by springs N and N', as plainly illustrated in the drawings. The under sides of the cups L and L' are engaged by the inner ends O² and O³ of levers O and O', fulcrumed at O⁴ and O⁵ on the sides of the part I, and the outer ends of the said levers O and O' are provided with plates O⁶ and O⁷ adapted 100 to be engaged by the inking rollers and pressed by the same in a downward direction, so that the inner ends O² and O³ of the levers O and O' impart a swing-

ing motion to the cups L and L', to swing the corresponding cup L or L' over onto the raised portion I⁴, to cover the same. Thus, if the printing roller P travels from the left to the right, in the direction of 5 the arrow a' (see Fig. 4), then it first comes in contact with the plate O⁷ and imparts a swinging motion to the lever O', which in turn imparts an upward swinging motion to the cup L', so that the advancing inking roller P strikes the back of the cup L' and swings the 10 same completely over onto the raised portion I⁴ to cover the same. As soon as the inking roller P has left the cup L', the spring N' thereof immediately causes the cup to swing back to its normal open position, and with it the lever O'. When the inking 15 roller P returns and travels in the inverse direction of the arrow a', then it engages the plate O⁶ and thereby imparts a swinging motion to the lever O, which in turn swings the cup L upward, so that the back thereof is engaged by the returning roller P, which now swings 20 the cup L completely over onto the raised portion I⁴ to completely cover the same. When the inking roller P has left the cup L, then the latter is immediately returned to its open position by the spring L². Thus, during the travel of the inking roller P in a for- 25 ward or backward direction, the raised portion I⁴ is covered by the cup L or L', and consequently the raised portion I⁴ is not inked and does not make an impression on the paper at the time the numbering wheels make their impression on the paper.

30 The construction of the numbering wheels C, ratchet-wheels D, pawl frame E, pawls E' and dogs F is practically the same as that of numbering apparatus as now constructed, and hence further detailed description of the same is not deemed necessary.

35 By having the interchangeable parts I and I', the printer can readily change the numbering apparatus from one with a prefix to one without a prefix, it being, however, understood that in either case the plate G, the coupling pin H, the part I or I' and the springs J 40 form a spring-pressed plunger for actuating the pawl frame E carrying the pawls E' employed for turning the numbering wheels.

Having thus described my invention, I claim as new and desire to secure by Letters Patent:—

45 1. A numbering apparatus for printing presses, comprising a casing, numbering wheels mounted to turn in the said casing, and an actuating device for turning the said numbering wheels, the actuating device having interchangeable prefix and non-prefix parts, the said parts 50 when in position having sliding engagement with the casing and adapted to be engaged by a part of the printing press for imparting movement to the said actuating device to turn the numbering wheels.

2. A numbering apparatus for printing presses, comprising a casing, numbering wheels mounted to turn in the said casing, an actuating device for turning the said numbering wheels, the actuating device having a movable part adapted to be engaged by a part of the printing press for imparting movement to the actuating device for the latter 60 to turn the numbering wheels, and means controlled by the inking roller of the press to cover the said part for preventing the inking roller from inking the part.

3. A numbering apparatus for printing presses, comprising a casing, numbering wheels mounted to turn in the 65 said casing, an actuating device for turning the said numbering wheels, the actuating device having a movable part adapted to be engaged by a part of the printing press for imparting movement to the actuating device for the latter to turn the numbering wheels, and a covering device on the

70 said movable part controlled by the inking roller of the printing press to cover the said part immediately previous to the inking roller passing over the numbering apparatus.

4. A numbering apparatus for printing presses, comprising a casing, numbering wheels mounted to turn in the 75 said casing, an actuating device for turning the said numbering wheels, the actuating device having a movable part adapted to be engaged by a part of the printing press for imparting movement to the actuating device for the latter to turn the numbering wheels, and a covering device on the 80 said movable part controlled by the inking roller of the printing press to cover the said part immediately previous to the inking roller passing over the numbering apparatus, the said covering device comprising a cup mounted to swing on the said movable part, and a lever fulcrumed on the said movable part and engaging with one end the 85 said cup, the other end of the lever being adapted to be pressed by the inking roller.

5. A numbering apparatus for printing presses, comprising a casing, numbering wheels mounted to turn in the 90 said casing, an actuating device for turning the said numbering wheels, the actuating device having a movable part adapted to be engaged by a part of the printing press for imparting movement to the actuating device for the latter to turn the numbering wheels, a covering device on the 95 said movable part controlled by the inking roller of the printing press to cover the said part immediately previous to the inking roller passing over the numbering apparatus, the said covering device comprising a cup mounted to swing on the said movable part and a lever fulcrumed 100 on the said movable part and engaging with one end the said cup, the other end of the lever being adapted to be pressed by the inking roller, and a spring pressing the said cup to return the latter and the said lever to a normal open position.

6. A numbering apparatus for printing presses, comprising a casing, numbering wheels mounted to turn in the said casing, an actuating device for turning the said numbering wheels, the actuating device having a movable part adapted to be engaged by a part of the printing press for imparting movement to the actuating device for the latter to turn the numbering wheels, a covering device on the 110 said movable part controlled by the inking roller of the printing press to cover the said part immediately previous to the inking roller passing over the numbering apparatus, the said covering device comprising cups pivoted on opposite sides of the said movable part and adapted to swing alternately over the said part to cover it, and levers fulcrumed on opposite sides of the said movable part and engaging the corresponding cups, the said levers 115 being adapted to be pressed by the inking roller of the printing press to swing the cups over into covering position.

7. A numbering apparatus for printing presses, comprising a casing, numbering wheels mounted to turn in the 125 said casing, an actuating device for turning the said numbering wheels, the actuating device having a movable part adapted to be engaged by a part of the printing press for imparting movement to the actuating device for the latter to turn the numbering wheels, a covering device on the 130 said movable part controlled by the inking roller of the printing press to cover the said part immediately previous to the inking roller passing over the numbering apparatus, the said covering device comprising cups pivoted on opposite sides of the said movable part and adapted to 135 swing alternately over the said part to cover it, levers fulcrumed on opposite sides of the said movable part and engaging the corresponding cups, the said levers being adapted to be pressed by the inking roller of the printing press to swing the cups over into covering position, and 140 springs for returning the cups and levers to a normal open position.

8. A numbering apparatus provided with an actuating device for the numbering wheels, said device having a movable part, and means for covering the said movable part 145 on the approach and passage of an inking roller.

9. A numbering apparatus provided with an actuating device for the numbering wheels the said device having a movable part, and means for covering the said movable

part on the approach and passage of an inking roller, the said means being controlled by the approaching inking roller.

10. A numbering apparatus provided with a casing, 5 numbering wheels, a spring pressed plunger, and means for operating the numbering wheels from the plunger, the said plunger comprising a plate and interchangeable prefix and non-prefix parts carried by the plate and having sliding movement on the casing.
- 10 11. A numbering apparatus, provided with a casing, numbering wheels, a spring pressed plunger provided with a member detachably secured thereto and having sliding movement on the casing, and means for operating the numbering wheels from the plunger.
- 15 12. A numbering apparatus provided with a casing, a shaft passing through the casing, numbering wheels on the said shaft and provided with ratchet-wheels, a pawl frame having pawls for engagement with the said ratchet-wheels, and a spring-pressed plunger mounted to slide up and down in the said casing and connected with the said pawl frame, the said plunger comprising a plate, a coupling pin 20 and interchangeable prefix and non-prefix parts adapted to be connected by the said coupling pin to the said plate, and a hook engaging a pin on the said plate for limiting the upward sliding motion of the said plunger.

and interchangeable prefix and non-prefix parts adapted to be connected by the said coupling pin to the said plate and to have guided movement on the casing.

13. A numbering apparatus provided with a casing, a shaft passing through the casing, numbering wheels on the said shaft and provided with ratchet-wheels, a pawl frame having pawls for engagement with the said ratchet-wheels, a spring-pressed plunger mounted to slide up and down in the said casing and connected with the said pawl frame, the said plunger comprising a plate, a coupling pin and interchangeable prefix and non-prefix parts adapted to be connected by the said coupling pin to the said plate, and a hook engaging a pin on the said plate for limiting the upward sliding motion of the said plunger. 25 30 35

In testimony whereof I have signed my name to this specification in the presence of two subscribing witnesses.
